UNITED STATES PATENT OFFICE

FRANK PERTOT, OF BROOKLYN, NEW YORK

HAT FORM

Application filed March 19, 1930. Serial No. 437,091.

This invention is directed to an improvement in hat forms of that type used in shaping machines, wherein the hat is given the final general shape.

5 Hat forms of this type, as hereinbefore provided have been constructed of rubber having a general hat shape, that is including a crown and brim, and the hat is brought to final general shape over this form. Owing to a 10 marked tendency of the hat material to stick to the rubber surface of the form, when directly applied thereto, it has been heretofore necessary to apply a covering for the form, over which covering the hat is formed. These 15 coverings, usually of silk, not only reduce the output of a particular machine but add to the expense of the operation, for the time required in applying and adjusting the covering, to say nothing of the expense of the covering itself, which requires frequent renewal, 20 are material factors in reduced output and increased expense.

The primary object of the present invention is the permanent application to the exterior of a rubber or like hat form of a canvas or duck covering, which by reason of its permanent application becomes an integral part of the hat form, and provides the very material advantage of absorbing any moisture in 25 or passing through the hat material and prevents adherence between the hat material and the rubber of the form.

A further object of the invention is the application of the permanent covering of canvas or duck in a manner to avoid any seam formation, so that the exterior of the form is completely smooth. This avoids the objection of the necessary seam in the removable covering referred to, and also avoids the marring of the interior of the hat by such seam. 30

The invention is illustrated in the accompanying drawing, in which:—

Fig. 1 is a perspective view of the improved hat form.

45 Fig. 2 is a side elevation, partly in vertical section, of the same.

The hat form is as usual constructed of rubber formed as an integral unit, and comprising the crown portion 1 and the brim portion 2. Heretofore this unit, when in use in 50

the shaping machine has been covered by a separate and removable covering of silk, which more or less closely fitted the crown and brim. This covering was found necessary to avoid the material of the hat from sticking to the rubber of the form. The hat material absorbs more or less moisture and if this were delivered onto the rubber form a considerable adherence between the hat material and form would result. Thus the covering of silk referred to is considered necessary, and of course this covering must be carefully placed on the form at each operation, and is subjected to such wear as to require frequent renewal.

In carrying the present invention into effect, the hat form, throughout the exterior of the crown portion and brim is covered with a layer of canvas or duck, as indicated at 3. This layer of canvas or duck is permanently secured to the rubber surface of the form, and it is to be particularly noted that such covering is applied in a manner to avoid any seams or projecting junctures. In other words, the covering when applied is practically as smooth as the rubber surface of the form, and thus any possibility of marring the hat incident to the shaping is avoided.

The advantages of the covering permanently applied will be at once appreciated. The fixed covering is permanent and does not have to be applied at each operation, nor is it necessary to renew it. The fixed covering will completely absorb all moisture which may find its way through the hat material, and from the nature of the material of the permanent covering, there is no possibility of the hat material sticking to the form.

The use of the form resulting from this invention tends to an increased production, as the time ordinarily consumed in applying and removing the silk loose form covering may be directed to the hat shaping, for the covering of the present form is permanent. Furthermore, as canvas or duck is used for the permanent covering, and silk or other thin material was required for the loose covering, there is a materially increased life in the permanent covering. Again, as the loose covering has to be shaped to fit over the rub-

ber form, the use of seams cannot be avoided, and such seams tend to mar the interior of the hat in shaping. With the permanent covering the canvas or duck is entirely free of seams or projections, and the possibility of marring the hat from such cause entirely avoided. The removable covering is capable of only limited use with the form, experience showing that a dozen of such forms are ordinarily required in each day's use of the machine. These forms thus constitute an item of more or less expense, while the permanent covering by being permanent in place and of a material which could not be used for the removable covering, have a materially greater life, and thus the overhead incident to this item is materially reduced in favor of the permanent covering.

It is highly important that the coating applied to the rubber form throughout the crown portion be smooth and without ridges or seams and, therefore, it is preferred that this covering be of canvas. The covering throughout the brim portion of the form may, and preferably is, of a material which has a greater absorbing quality than that of canvas as, for example, felt, indicated at 4. The felt is, of course, more absorbing than the canvas and is also somewhat more rough, but this is not a disadvantage at the particular place at which the felt is applied. Furthermore, felt can be more easily fitted to the form than can canvas.

Having thus described the invention, what is claimed as new, is:—

1. A hat form for shaping machines constructed of rubber, and a covering of canvas permanently secured to the exterior shaping surface of such form.
2. A hat form of rubber, a covering of canvas throughout the crown portion of such form, and a covering of felt throughout the brim portion of such form.
3. A hat form for shaping machines constructed of substantially resilient material, a permanently applied surface covering of a material inherently moisture-absorbent, and adhesive means for securing the surface covering material in place, said surface covering means being resistive to the complete penetration of the adhesive means.

In testimony whereof I affix my signature.

FRANK PERTOT. [L. s.]
